UNITED STATES PATENT OFFICE.

HERBERT S. PULLMAN, OF ROCKVILLE, ASSIGNOR TO CHARLES E. BILLINGS,
OF HARTFORD, CONNECTICUT.

PIPE-TONGS.

SPECIFICATION forming part of Letters Patent No. 295,885, dated March 25, 1884.

Application filed February 6, 1884. (No model.)

To all whom it may concern:

Be it known that I, HERBERT S. PULLMAN, of Rockville, in the county of Tolland and State of Connecticut, have invented certain new and useful Improvements in Pipe-Tongs; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

Figure 1 is a side view of a pair of pipe-tongs embodying my improvement. In this view one of the jaws is shown in dotted outline in the position the parts must be placed in to change the adjustment of the jaws. Fig. 2 is a side view of the same tongs with the jaws 20 adjusted to grasp larger objects than as first shown. The head of the fulcrum-stud is broken away to show the shank. Fig. 3 is a view in cross-section through the parts, on line $\alpha\alpha$ of Fig. 2.

My improvement relates to the class of pliers or tongs that are made with means for varying and adjusting the jaws so as to grasp objects of small or comparatively large diameter, and particularly to the special class of pipe-tongs used for coupling and uncoupling pipes, or putting on or removing gas-jets and the like.

It consists in a pair of lever-handles bearing jaws, and so pivoted together by means of a stud or fulcrum-pin working in a series of 35 sockets joined by a slot that the jaws may be adjusted between the limits determined by the extreme sockets by sliding the handles on each other edgewise, and without removing them from contact during this adjustment.

In the accompanying drawings, the letters a and b denote two lever-handles, usually of metal—as steel—bearing as their short arms jaws c and d , that are counterparts of each other. These jaws may be made with the flat pincher-faces e at their nose, with the irregular opening f nearer the pivot-stud g , on which the levers fulcrum and turn, this opening being faced with pipe-grasping teeth of the usual outline, and still nearer the pivot the wire-cutters h .

The end of one of the lever-handles may be made in proper form to serve as a screw-

driver, as at a' ; but these particular features of jaws and handles are not material to my improvement, that relates particularly to the adjustability of the jaws. This term, as herein used, I wish to limit in its meaning, so that it applies only to the edgewise movement of the jaws in changing the pivot-bearings, and not to the changing of the angle of the jaws caused by opening or closing the lever-handles. One of the lever-handles b bears on one side the pivot-stud g , that projects into, and in the form shown, through the fulcrum-sockets i or i' , terminating in a broadened head, g' , while the shank of the stud is flattened on opposite sides, so as to be oblong in section. The sockets i i' , of which there may be any desirable plural number, are preferably of uniform diameter, and they are joined by a slot, k , narrower in width than the sockets are in diameter. The shank of the stud in its widest section bears on opposite faces of a socket, the said stud forming the fulcrum of the lever-handles in operating the tool; and to adjust the jaws wider apart, as seen in Fig. 2, the handles are turned on the stud to about ninety degrees with each other. They may then be slipped edgewise in opposite directions until the stud has passed into the next socket, (see the dotted outline in Fig. 1,) the narrow part 70 of the shank passing through the slot. By reversing this operation the jaws may be adjusted to their inner limit, and these adjustments repeated at any time at will.

I claim as my invention—

1. As an improved article of manufacture, pivoted lever-handles with jaws substantially as described, one handle bearing a stud, with a shank of oblong section, and the other handle having a plural number of socket-bearings joined by a narrowed slot, all substantially as described.

2. The combination of lever-handles a and b , having jaws c and d , the handle a bearing the pivot-stud g , with oblong shank, and the handle b having a plural number of sockets, i i' , joined by the slot k , whereby the jaws may be adjusted, all substantially as described.

HERBERT S. PULLMAN.
